To all whom it may concern:

Be it known that I, Carl Colcord, a citizen of the United States of America, residing in the city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a front view of the dress portion of the dress ensemble.

Fig. 3 is a rear view of Fig. 2.

The rear of the jacket portion of the ensemble is conventional in cut.

The characteristic feature of my design resides in the combination on the ensemble disclosed of the specific lace jacket and matching lace corsage on the specific dress as shown.

I claim:

The ornamental design for a dress ensemble substantially as shown and described.
